CLAIM

The ornamental design for a computer keyboard with a curved top configuration, as shown and described.

DESCRIPTION

FIG. 1 is the reduced perspective view of a design for a computer keyboard with a curved top configuration showing my design;

FIG. 2 is the front elevational view thereof;

FIG. 3 is the rear elevational view thereof;

FIG. 4 is the left side elevational view thereof;

FIG. 5 is the right side elevational view thereof;

FIG. 6 is the top plan view thereof;

FIG. 7 is the bottom plan view thereof; and,

FIG. 8 is the enlarged fragmentary perspective view of a portion of the keyboard as shown in FIG. 1 for clarity of illustration.

FIG. 1

FIG. 2

FIG. 3

FIG. 4

FIG. 5

FIG. 6

FIG. 7

FIG. 8
